UNITED STATES PATENT OFFICE.

JULIUS C. TORCHIA, OF HAZLETON, PENNSYLVANIA.

FASTENER-INSERTING MACHINE.

1,274,817.

Specification of Letters Patent.

Patented Aug. 6, 1918.

Application filed October 23, 1917. Serial No. 193,121.

To all whom it may concern:

Be it known that I, JULIUS C. TORCHIA, a citizen of the United States, residing at Hazleton, in the county of Luzerne and State of Pennsylvania, have invented certain new and useful Improvements in Fastener-Inserting Machines, of which the following is a specification.

My invention relates to that class of machines known as "string nailing machines" and has special reference to improvements in machines of the type shown in Patent No. 1,091,298, granted March 24, 1914 to G. A. and S. A. Dobyne.

The particular object of the present improvements is to provide means whereby the blade carrying arm will be positively moved to engage and feed the nails and also to provide means whereby the blade will be effectively restrained so as to withstand the shock placed thereon while severing a nail from the string of nails. The invention also seeks to provide a device for the stated purposes, which will be simple in construction and readily manipulated to permit adjustment of the blade.

The invention is illustrated in the accompanying drawings, in which—

Figure 1 is an elevation of so much of a nailing machine as is deemed necessary to a complete understanding of my improvements.

Fig. 2 is a detail perspective view of the bracket and adjusting screw employed in the application of my invention.

The nailing machine comprises a standard 1, on which is provided a guide 2 for the fastener stock or string of nails, a portion of which is shown at 3. An operating lever 4 is fulcrumed at 5 and vibrated by suitable cam mechanism, which is not illustrated herein as it forms no part of my invention. To the lower end of the lever 4 is pivoted, as at 6, a knife-carrying arm 7, the said arm being provided at its lower end with clamping plates 8 which engage the side edges of the feeding and cutting blade 9 and are secured to the arm, so as to clamp the blade, by a screw or similar fastening 10. In the operation of the machine, as the lever 4 moves upwardly, the blade-carrying arm 7 is intended to move about its pivot 6 so that the blade will ride upwardly along the guide 2 and engage the head of a nail so that, upon the return movement, the nails will be fed to the work, the continued movement of the

driving mechanism causing the blade to sever the lowest nail from the string. To cause the blade carrying arm to positively perform this allotted function, I employ a coil spring 11 which is connected at its lower end with the screw 10 and has its upper end attached to the lever 4, as clearly shown. It will be noted that this spring lies substantially parallel with the stock or string of fasteners and will therefore exert a direct upward pull upon the blade so that the blade will not be apt to move away from the fasteners but will be held to and positively engage and feed the same. In order to maintain the string of fasteners in its proper position parallel with the said spring and in line with the guide 2, I provide an upper guide or eye 12 which is held in place by the head of the fulcrum screw or bolt 5 so that the string of fasteners will extend in a straight line from the said upper guide to the main guide 2 and will not be liable to become entangled with the retracting spring 11.

In the actual use of string nailing machines of the type noted, the blade would give way under the strain imposed thereon in cutting through the nails and would slide endwise outwardly between the clamping plates 8. To overcome this objection and to permit the blade to be adjusted so as to compensate for wear and properly cut through the nails, I provide an adjusting screw 13 which is mounted in the lower end of a bracket 14 and is held in a set position by a lock nut 15. The bracket 14 consists of a substantially U-shaped body or base portion 16, the members of which are adapted to fit on opposite sides of the blade carrying arm 7, and a neck 17 extending downwardly from the said base or body, an internally threaded eye or loop 18 being provided at the extremity of said neck. The adjusting screw or bolt 13 is inserted through and engaged in the internally threaded eye 18 and is equipped at its outer end with a handle 19, of any convenient form, whereby it may be readily rotated and thereby caused to move through the eye. The lock nut 15 will preferably be of circular form and equipped with a plurality of sockets 20, in which any convenient tool may be engaged so as to turn the nut about the screw. The bracket 14 is secured to the blade-carrying arm 7 by a screw or bolt 21 inserted through the body or base portion of the bracket and

the said arm, and having a smooth unthreaded portion upon which the bracket may turn pivotally. At the forward corners of the base portion, additional openings 22 are provided and a pin 23 is inserted through these openings and the blade-carrying arm to retain the bracket in operative position.

It is thought the manner of using my adjusting device will be readily understood. 10 The pin 23 is withdrawn and the bracket swung downwardly and outwardly about the pivot screw 21, so that the adjusting thrust-screw 13 will be away from the blade. The blade is then adjusted so that it will 15 have the proper relation to the nails, after which the bracket is returned to its normal position, which is illustrated in Fig. 1. The adjustable thrust screw 13 is then rotated so as to move through the eye 18 until its forward end bears against the outer rear end of the blade, as clearly shown in Fig. 1. The nut 20 is then rotated about the screw so that it will ride home against the forward side of the eye 18 and will consequently hold the screw in its adjusted position and by its engagement with the front side of the eye 18, will prevent the screw moving rearwardly through the same, the blade consequently being held to its work 25 30 and prevented from moving outwardly between the clamping plates 8, under the strain placed thereon.

From the foregoing description, taken in connection with the accompanying drawings, it will be seen that I have provided an exceedingly simple device which may be readily applied to machines now in use and by which the outward movement of the knife will be positively prevented so that after 35 40 it has been once adjusted, no further adjustment will be needed except to compensate for the ordinary wear upon the cutting edge. The strain upon the retaining screw 10 is very materially reduced so that said screw is not required to perform any work 45 in holding the blade in position and need be only heavy enough to hold the clamping plates to the blade. The blade will not be supported by the plates 8 alone, but will be held to its work by the adjusting screw 13, which receives the thrust. An unskilled workman may readjust the blade in a very few minutes or may substitute a new blade for a worn out blade without any great loss 50 55 of time and, when the parts are in the operative position, the thrust receiving adjusting screw 13 will be substantially in the

same plane as the blade so that it will act positively thereon and will not induce a twisting action of the blade. 60

Having thus described the invention, what is claimed as new is:

1. In a machine of the character set forth, the combination of a supporting structure, a guide thereon, a lever fulcrumed upon the supporting structure above the guide, a second guide held by the fulcrum of the lever in alinement with the first-mentioned guide, a blade carrying arm pivoted to the lower end of the lever, a blade carried by said arm to feed and sever fasteners passing through the said guides, a bracket secured to and projecting downwardly from said arm above the lower end thereof, a thrust-receiving member mounted in the lower end of said bracket and held thereby against the blade and in spaced relation to the arm, means on said member between the blade and the bracket to engage the bracket and prevent movement of the member from the blade, and a retractile spring having its lower end connected with the lower end of the blade carrying arm and its upper end attached to the lever adjacent the fulcrum thereof whereby the spring will extend substantially parallel with a string of fasteners passing through the said guides. 75 80 85

2. In a machine of the character set forth, the combination of a blade carrying arm, a blade mounted upon the lower end of said arm, a bracket secured to said arm above the lower end thereof and projecting downwardly therefrom and beyond the under side thereof, a thrust receiving member threaded through the lower end of said bracket to bear against the rear end of the blade, and a locking device mounted on the thrust-receiving member between the blade and the bracket to bear against the front side of the bracket. 90 95 100

3. In a machine of the character set forth, the combination of a blade-carrying arm, a blade mounted upon the lower end of said arm, a bracket pivoted to said arm and projecting beyond the under side of the same, means for holding the bracket normally against pivotal movement, a thrust-receiving member mounted in the lower end of said bracket and bearing against the outer end of the blade, and means for preventing outward movement of said thrust-receiving member. 105 110

In testimony whereof I affix my signature:
JULIUS C. TORCHIA. [L.S.]
